J. M. WEILER

CLOTHES DRIER

Filed May 28, 1925

UNITED STATES PATENT OFFICE.

JOSEPHINE M. WEILER, OF LISBON, NORTH DAKOTA.

CLOTHES DRIER.

Application filed May 28, 1925. Serial No. 33,517.

To all whom it may concern:

Be it known that I, JOSEPHINE M. WEILER, a citizen of the United States, residing at Lisbon, in the county of Ransom and State of North Dakota, have invented certain new and useful Improvements in Clothes Driers, of which the following is a specification, reference being had to the accompanying drawings.

10 This invention relates to clothes driers and racks of like character, and particularly to those clothes driers wherein arms are provided which may be shifted from a depending inoperative position to an outwardly extending horizontal position.

15 The general object of the invention is to provide a rack of this character wherein the arms or clothes supports are mounted upon a central hollow body which is so constructed that the arms operate through apertures formed in the shell so that when the arms are in their inoperative and depending position they are inside the shell and entirely protected from dust and dirt.

20 25 A further object is to provide a device of this character having a hollow, central shell mounted upon a wheeled support so that the device may be readily shifted to any desired place, the shell providing for the support of a large number of radially directed clothes-drying arms, these arms, however, being collapsible into position within the shell so that the shell with its depending arms will take up but very little room.

30 35 Other objects will appear in the course of the following description.

My invention is illustrated in the accompanying drawing, wherein:

40 45 Figure 1 is a side elevation of a clothes drier constructed in accordance with my invention;

Figure 2 is a fragmentary sectional view on a larger scale and on the line 2—2 of Figure 1 but showing one of the arms extended;

Figure 3 is a like view to Figure 2 but showing one of the arms retracted;

Figure 4 is a section on the line 4—4 of Figure 3;

Figure 5 is a sectional view on the line 5—5 of Figure 1.

Referring to this drawing, 10 designates a hollow, metallic shell which is supported

upon a central standard 11 in any suitable manner, this standard having attached thereto the outwardly projecting legs 12 and these legs at their extremities carrying the casters 13. The shell at a plurality of different levels is formed with a circularly extending series of apertures 14 formed by punching out approximately triangular openings in the metal of the shell, a portion 15 of the metal being retained and bent inward at right angles, as at 16. This portion 16 and the shell immediately below this inwardly projecting tongue 16 is slotted at 17 and the lower end of this slot is reinforced by a reinforcing piece 18 which is riveted to the metal.

Attached to the inside face of the shell and extending over each opening 15 is a plate 19 which is riveted to the shell which is approximately triangular in form and which is stamped out to provide an upwardly and outwardly tapering brace 20 which at its lower edge bears against the inwardly turned tongue 16. This plate is riveted, soldered or otherwise attached to the inner face of the shell and the tongue 16 at its extremity is preferably formed with a lug 21 having interlocking engagement with a slot 22 formed upon the lower end of the bracing portion 20.

Disposed through each slot 17 is an arm 23 which has a width slightly less than the width of the slot 17 and any desired length. This arm at its inner end is formed with a transversely extending pin 24 which is wider than the width of the slot 17 and at its outer end the arm may be provided with a ring 25 or any stop. When the arm is collapsed it hangs down within the shell 10 in the manner illustrated in Figure 3, the ring or other stop 25 resting upon the inwardly projecting tongue 16 and extending across the slot therein so that the arm cannot drop through.

When the arm is in use, it is pushed outward in an obvious manner until the pin 24 engages against the shell and then the arm is supported in a horizontal position with the rear extremity of the arm bearing upward against the tongue 16 and, of course, the weight of the arm and the clothes resting thereon being supported by the downwardly extending brace plate 19 and particularly the portion 20 thereof. The cor-

rugating of this brace plate by forming this outwardly bulged middle portion 20 strengthens this brace plate very greatly and provides a support which acts to strengthen 5 the shell itself and also bear the full weight of the arm 23.

It will be noted from Figure 1 that the openings 15 of one series of openings are in 10 staggered relation to the openings of the next adjacent series so that one series of arms hangs down between the next adjacent 15 series of arms. The top 26 of the shell 10 is also formed with a series of slots 17, these slots extending downward through the top of the shell, and arms 23 are disposed in these slots and operate in precisely the same manner.

I have illustrated the shell 10 as formed 20 with four series of arms and the openings 15 for these arms, but I do not wish to be limited to this as it is obvious that it might be formed with a greater number of series 25 of arms. It is also obvious that the arms may be made of different lengths, the lower arms being longer than the upper arms, or vice versa, or all of the arms may be of the same length, but it will be also seen that this construction provides for the use of a large number of radiating arms by reason 30 of the fact that the shell has a, relatively speaking, large diameter so as to accommodate a great many arms and that inasmuch as these arms radiate they will be sufficiently spaced from each other as to permit the hanging of a large number of clothes thereon. If there was a central staff or standard 35 to which these arms were attached, only a relatively few arms could be mounted upon the central staff or standard and thus the 40 device would not permit the use of anywhere near the number of arms that are permitted by my construction. It is to be particularly noted that the tapered form of shell 10 permits of the use of a plurality of series of 45 arms for the reason that the upper arms, when they are slipped inward, will hang down inside of the next lower series of arms and these in turn inside of the next lower 50 series of arms, thus permitting the device to be made with a relatively large number of arms arranged at various heights.

The shell 10 may be made of galvanized 55 or enameled metal so that damp or wet clothes hung upon the rack will not affect the metal in any way. The arms mounted upon the cylindrical cone 10 will have a linear length of drying space of about seventy feet and ball bearing casters allow the 60 drier to be revolved and loaded from one position. It is obvious, of course, that the shell may be rotatably mounted upon the central support 11 so that the shell can be revolved to bring any desired arm into position. This may be accomplished by simply mounting the upper end of the shell 65

upon a suitable support carried by the member 11. The construction of such a support will be obvious.

In order to permit the removal and insertion of the arms 23, I may provide the 70 shell 10 with a hand hole 27 provided with a cover 28 which is pivoted so as to swing over the hand hole. This permits the insertion of the hand and the removal of the arms 23 from inside the shell. 75

While I have illustrated certain details of construction and arrangement of parts which I believe to be particularly effective, I do not wish to be limited thereto as it is obvious that many changes might be made 80 in the details without departing from the spirit of the invention as defined in the appended claims:

I claim:—

1. A clothes hanger of the character described 85 including a hollow, metallic, upwardly tapering shell having a plurality of circumferentially arranged series of openings, the lower edge of each opening being provided with an inwardly projecting slotted member and the lower margin of each opening being slotted, the slots merging with each other, and arms, one for each opening, slipping longitudinally through said slots, the arms being formed with stops 90 at their opposite ends, the arms when in a projected position engaging against the under face of the corresponding inwardly extending member, the tapering form of the shell permitting an upper series of arms to 100 be disposed in a vertical position inward of a lower series of arms.

2. A clothes rack of the character described including a thin metallic member 105 having an approximately triangular opening, there being a horizontally disposed tongue extending inward from the lower end of said opening, the horizontal tongue and the metal at the lower margin of said opening being slotted, said slots merging 110 into each other, an arm sliding through said slot and formed with stops at its opposite ends, whereby the arm may be supported in a vertical position by the said metallic member or in a horizontal position projecting 115 outward therefrom, and a bracing member attached to the inner face of the metallic member and bearing against said tongue.

3. A clothes drier of the character described 120 including a hollow shell, the shell being provided with a plurality of circumferentially arranged series of openings, each opening being approximately triangular in form and the lower wall of the opening having an inwardly projecting tongue, the tongue and the shell immediately below the tongue being slotted, the slots merging into one another, an arm extending through said slot, the inner and outer ends of the 125 arm being provided with a stop, and an 130

upwardly tapering, transversely curved bracing member of sheet metal attached to the shell upon the inside face thereof and behind each opening, said bracing member 5 extending downward and inward and bearing against the margin of said tongue.

4. A clothes drier of the character described including a hollow shell, the shell being provided with a plurality of circumferential series of openings, each opening being approximately triangular in form and the lower wall of the opening being provided with an inwardly projecting tongue, the tongue and the shell immediately below the tongue being slotted, the slots merging into one another, an arm extending through said slot, the inner and outer ends of the arm being provided with a stop, an upwardly tapering, transversely curved bracing member of sheet metal attached to the shell upon the inside face thereof and behind each opening, the bracing member extending downward and bearing against the margin of said tongue, the lower end of said 20 bracing member being formed with a locking slot and the tongue at its extremity

having a lug engaging in said locking slot.

5. A clothes drier of the character described including a hollow shell, legs supporting the shell and having wheels, the shell being formed with a plurality of circumferentially extending series of apertures, the apertures being approximately triangular in form and the lower end of each aperture being provided with an inwardly 30 projecting tongue struck out from the aperture, the tongue and the shell immediately below the same being slotted, the slots merging into one another, a clothes supporting arm rectangular in cross section 35 fitting said slot and slidable inwardly or outwardly through the same, the arm being provided at opposite ends with stops whereby the arm may be disposed in a vertical position entirely within the shell or in a horizontal position projecting therefrom, and bracing means engaged with the inner 40 face of the shell and extending downward and bearing against the tongue.

In testimony whereof I hereunto affix my 50 signature.

JOSEPHINE M. WEILER.
